(57) **CLAIM**

The ornamental design for a counter for banknote sorting machine, as shown and described.

DESCRIPTION

FIG. 1 is a perspective view of a counter for banknote sorting machine, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof; and,

FIG. 8 is another perspective view thereof, shown in a position of use with additional environment.

The broken lines in FIG. 8 depict environment only and form no part of the claimed design.

All other broken lines depict portions of the counter for banknote sorting machine that form no part of the claimed design.
